UNITED STATES PATENT OFFICE.

BERT G. DUNHAM, OF HAWTHORNE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,270,388.

Specification of Letters Patent. Patented June 25, 1918.

Application filed November 20, 1916. Serial No. 132,373.

To all whom it may concern:

Be it known that I, BERT G. DUNHAM, a citizen of the United States, residing at Hawthorne, in the county of Passaic and 5 State of New Jersey, have invented certain new and useful Improvements in Telephone-Exchange Systems, of which the following is a full, clear, concise, and exact description.

10 This invention relates to telephone exchange systems wherein automatic finder switches are apportioned to calling lines by an extended starter wire, and is an improvement upon the system disclosed in my 15 Patent No. 1,205,523, granted November 21, 1916.

In systems of this character a relay is provided at each finder for disabling its release circuit, the relays of busy finders being included in the starter wire when the 20 starter wire is extended through such busy finders. When such starter wire is grounded by the initiation of a call, to start the finder to which the starter wire is extended, the 25 relays of such busy finders through which the starter wire extends are energized to prevent release of such finders, since the release of an intermediate finder would disrupt the starting circuit.

30 It was found in practice that, with the circuit arrangement of said patent, if all the finders were busy and another call was initiated, the finders could not be released as long as the calling party had his receiver 35 off the switchhook, since the disabling relays were held energized as long as the calling line circuit was closed.

By virtue of the present invention, this 40 cannot occur, and the improvement consists in providing an electromagnetic responsive device for the group of finders which is operated over a circuit closed when all the finders are busy, and which, when operated, prevents the operation of said disabling relays.

The invention will be more readily understood when described with reference to the accompanying drawings, wherein Figures 1 and 2 illustrate one embodiment of the 50 invention.

Upon the removal of the receiver at substation E, the line relay e is energized over the line circuit. This relay, in attracting its inner armature, grounds the multiple 55 101 of the calling line, and, in attracting

its outer armature, energizes relays a, b, common to the group of lines containing substation E. Relay a, in attracting its right armature, grounds multiple segment 104 of the group to which substation E belongs to render the group calling. Relay b, in attracting its right armature, closes the following circuit to energize the escape magnet 106 of the line finder side switch: conductor m grounded at the armature and 60 back contact of the calling supervisory relay in the same manner as is disclosed in the before-mentioned Patent No. 1,205,523 of the automatic or manual switch to which conductors 121, 122, 125 and m are connected, 65 right armature and front contact of relay b, conductor 108, armatures and back contacts of magnets 107, 105, arm 1 of the finder side switch and its first contact, escape magnet 106 of the finder, and magnet 105 to free 70 pole of battery. Magnet 105 is marginal and is not energized in this circuit. The escape magnet 106 is constructed to release the side switch from position to position, 75 upon its energization.

In position 2, arm 1 of the finder side switch connects magnet 105 over the back contacts of magnets 105, 107, to grounded conductor 108, whereupon the finder brush shaft 119 is given a primary movement by 80 the operation of such magnet 105. In position 2, arm 2 closes the following circuit for relay 116: free pole of battery, magnet 107, arm 2, left winding of relay 116, armature and back contact of magnet 107 to 85 grounded conductor 108. This relay attracts its armature upon the closure of this circuit, but magnet 107 is marginal and remains inert. Relay 116, at its inner armature and front contact, connects the escape 90 magnet over arm 3 and its second contact to the group brush 115. When brush 115 encounters the calling group segment 104, now grounded, escape magnet 106 energizes over the following circuit, and releases the 95 side switch into position 3: free pole of battery, magnets 105, 106, conductors 117, 118, inner armature and front contact of relay 116, arm 3 and its second contact, conductors 120, 130, brush 115, segment 104, now 100 grounded at the armature and front contact of relay a. Arm 1, in moving out of position 2, opens the circuit of magnet 105, thus stopping the primary movement of the 105 finder brush shaft 119 with a set of brushes 110

110, 111, 112 in operative relation to multiples of the calling line group containing those of the calling line 101, 113 and 114.

In position 3, relay 116 is energized over the following circuit: free pole of battery, magnets 105, 106, arm 2 and its third contact, left winding of relay 116, armature and back contact of magnet 107, grounded conductor 108. Magnet 106 is also marginal and neither this magnet nor magnet 105 becomes energized in this circuit. Relay 116, at its outer armature and front contact, closes the following circuit to operate the secondary stepping magnet 107 to drive the brushes 110, 111 and 112 over the multiples containing those of the calling line 101, 113 and 114: free pole of battery, magnet 107, outer armature and front contact of relay 116, arm 1 and its third contact, armature and back contacts of magnets 105, 107, to grounded conductor 108. The magnet 107 interrupts the circuit traced through the left winding of relay 116, as well as its own circuit, and this relay therefore vibrates except when the brush 112 engages the test multiples 114 of busy lines, when it is held energized from battery on such terminals, brush 112, conductor 120, arm 3 and its third contact, right winding of relay 116, to ground, as will be more particularly described hereinafter. When, however, the brush 112 reaches the calling line multiple 114, relay 116 becomes deenergized, and in retracting its outer armature, interrupts the stepping circuit of magnet 107, thus arresting the brushes 110, 111, 112 on the calling line terminals 101, 113, 114. Since ground is present on multiple 101 of the calling line, the following circuit is closed to energize escape magnet 106: free pole of battery, magnets 105, 106, conductors 117 and 118, inner armature and back contact of relay 116, arm 5 and its third contact, brush 110, terminal 101 to ground at the inner armature and front contact of relay *c*. Magnet 106, upon its energization, releases the side switch into position 4. In position 4, the calling line is extended by arms 4 and 5 to the conductors 121, 122, whereupon the calling supervisory relay referred to is energized over the calling line circuit, and removes ground from conductor *m*.

In position 4, arm 3 of the finder side switch closes the following circuit to energize the cutoff relay *d* of the calling line: free pole of battery, resistance 190, conductor 125, arm 3 and its fourth contact, conductor 120, brush 112, terminal 114, cutoff relay *d*, to ground. This potential applied to multiples 114 by brush 112, holds relay 116 of a moving finder energized over its right winding as the brush 112 of such finder wipes over such multiples, as hereinbefore described. Relay *d*, in attracting its armatures deenergizes the line relay *e*, which

in retracting its inner armature, removes the calling condition from the multiples 101 of the calling line, and in retracting its outer armature, deenergizes group relays *a*, *b*. Relay *a*, in retracting its right armature, removes the calling condition from the multiples 104 of the calling group.

The switch connected to conductors 121, 122 to which the finder has extended the calling line *E*, may be either a manual or an automatic switch dependent upon the type of system.

Upon the termination of the conversation and the replacement of the receiver by the calling party, the supervisory relay connected to conductors 121, 122 becomes deenergized and closes the following circuit for the release magnet 127 of the finder: grounded conductor *m*, right armature and back contact of relay *b*, primary off-normal contact 126, release magnet 127, free pole of battery. Magnet 127, in attracting its left armature, locks itself over the off-normal contact 126 to ground. When the finder brush shaft 119 is completely restored, this off-normal contact opens and unlocks the release magnet. The magnet 127 also restores the side switch which opens the circuit of the cut-off relay *d*.

Going back to that point in the operation where the removal of the receiver starts a finder seeking the calling line, it will be remembered that the initiation of such call energized group relay *b*, which, in attracting its right armature, extended the conductor *m* grounded at the armature and back contact of the calling supervisory relay, to the escape magnet 106 to initiate the primary movement of the finder brush shaft. In parallel with magnet 106, a quick acting relay *c* is energized when relay *b* operates, this circuit being as follows: free pole of battery, relay *c*, spring *i*, conductors 133, 117, arm 1 and its first contact, armatures and back contacts of magnets 105, 107, conductor 108, right armature and front contact of relay *b* to grounded conductor *m*. Relay *c*, by attracting its right armature, locks itself directly to grounded conductor 108, independently of side-switch arm 1, and by attracting its left armature, opens the connection between the grounded left-hand armature of relay *a* and the out-starter wire *g*, leading to the escape magnet 106 of the next finder. If the finder shown in Fig. 1 had been busy, the calling supervisory relay would have been energized, and consequently the circuit for relay *c* just traced would not have been completed, and this relay failing to energize, the grounded left-hand armature of relay *a* would be connected over the left armature of relay *c* to the out-starter wire *g* leading to the escape magnet 106 of the next finder, to set the finder shaft in motion seeking the call-

ing line. Thus, the starter wire is normally extended to the next idle finder. Assuming the finder shown in Fig. 1 to be the next idle finder, the circuit may be continued as follows: in-starter wire f , left armature and back contact of relay a , relay b , conductor h , right armature and back contact of magnet 127, resistance 137, free pole of battery. Relay b , in attracting its left armature, connects the in and out-starter wires f and g together, and in attracting its right armature, energizes the escape magnet 106 of such finder as described, which, upon energizing, releases the side switch into position 2 to initiate the primary movement of the finder brush shaft. From this point on, the operations are the same as those already traced. The foregoing is shown and described in my patent referred to, and the improvement thereon, which is the subject matter of the present invention, will now be described.

It was found in practice that, with the circuit arrangement of said application, when all the finders were busy, an incoming waiting call would prevent the release of such finders, which release would ordinarily automatically take place upon the disconnecting act of the parties to the connections. This will be explained more particularly by reference to Fig. 2, wherein four sets of group relays a, b, c, a', b', c' , etc., and one line and one cut-off relay e, d , respectively, of a line in each group are shown. Assume that the four finders allotted to the four groups A, B, C, D, are busy and that one of the lines in group A initiates a call.

In the circuit arrangement of the patent referred to, the outer armature of relay e was permanently grounded. If all the finders were busy, the energization of relay e by the initiation of a call closed the circuit of relays a, b of group A in series, by way of conductor h (Figs. 1 and 2). Relay b in operating interposes a break in the circuit of the release magnet 127 to which conductor h is connected to prevent the energization of such release magnet, and consequent deenergization of relays a and b . Relays a and b in operating closed the following circuit to energize relay b^3 of the finder of group D, the next finder in so far as the starter wire is concerned: ground, left armatures and front contacts of relays a and b , left armature and back contact of relay c , not energized due to the absence of ground on conductor m , out starter wire g , left armature and back contact of relay a^3 of the group D, relay b^3 , conductor h^3 to battery, over the right armature and back contact of release magnet 127 of the finder group D. Relay b^3 in attracting its right armature interposes a break in the circuit of release magnet of the finder of group D, to which conductor h^3 is connected, and in

attracting its left armature closes the following circuit for relay b^2 of group C; grounded conductor f^3 , left armature and front contact of relay b^2 , left armature and back contact of relay c^3 , conductors g^3, f^2 , 70 left armature and back contact of relay a^2 , relay b^2 , conductor h^2 , to free pole of battery over the right armature and back contact of the release magnet 127 of the finder of group C. Relay b^2 in attracting its right armature interposes a break in the circuit of release magnet of the finder of group C, and, in attracting its left armature, closes the following circuit for relay b^1 of group B: grounded conductor f^2 , left armature 80 and front contact of relay b^2 , left armature and back contact of relay c^2 , conductors g^2, f^1 , left armature and back contact of relay a^1 , relay b^1 , conductor h^1 , to free pole of battery over the left armature and back contact of release magnet 127 of the finder of group B. Relay b^1 interposes a break in the circuit of such release magnet. It will thus be seen that the relays b, b^1, b^2 and b^3 , etc., are all energized under the control of 90 the line relay of the calling subscriber, and that inasmuch as these relays in attracting their right armatures interpose a break in the release circuits of the respective finders, none of these finders can release. To prevent this from occurring a slow relay 180 is provided.

When the finders of groups A, B, C, D, etc., are busy, the side switches of such finders are in their fourth position, and a 100 circuit is closed for such slow relay 180, over arms l, l^1, l^2, l^3 in series to ground. This relay in attracting its armature removes ground from the outer armatures of the line relays e, e^1, e^2, e^3 , etc., thus preventing the energization of any of such relays from operating the group relays a, b , and tying up all the finders as described. When, however, one of the finders is restored, the circuit of relay 180 is interrupted at the 110 corresponding side-switch arm l, l^1, l^2, l^3 , etc., whereupon relay 180 retracts its armature, reconnecting ground to the outer armatures of the line relays e, e^1, e^2, e^3 , etc., whereupon the energization of any of such 115 relays will operate the corresponding group relays and start such idler finder in motion seeking a calling line.

Relay 180 is made slow to retract its armature so that by the time the armature reaches its back contact the released finder and its side switch will have fully restored.

What is claimed is:

1. In a telephone exchange system, the combination with telephone lines, line relays for said lines, automatic finder switches, an extended starter wire for associating an idle finder with said lines, release circuits therefor, a relay associated with each finder for rendering its release circuit inoperative, 125 130 135

means actuated by the energization of any line relay for operating the relays of the finders through which the starter wire is extended, of a device for preventing the operation of said means, and means for operating said device automatically actuated when all of said finders are busy.

2. In a telephone exchange system, the combination with telephone lines, line relays for said lines, automatic finder switches, an extended starter wire for associating an idle finder with said lines, off-normal contacts associated with said finders, release circuits for said finders, a relay associated with each finder for rendering its release circuit inoperative, means actuated by the energization of any line relay for operating the relays of the finders through which the starter wire is extended, of a relay for preventing the operation of said means, and a circuit for said relay including the off-normal contacts of all of said finders in series.

3. In a telephone exchange system, the combination with telephone lines, line relays for said lines, automatic finder switches, side switches therefor, an extended starter wire for associating an idle finder with said lines, release circuits for said finders, a relay associated with each finder for rendering its

release circuit inoperative, and means actuated by the energization of any line relay for operating the relays of the finders through which the starter wire is extended, of a slow relay for preventing the operation 35 of said means, and a circuit for said relay including side-switch arms of all of said finders in series.

4. In a telephone exchange system, the combination with telephone lines, line relays therefor, automatic finder switches, an extended starter wire for associating an idle finder with said lines, off-normal contacts therefor, release circuits for said finders, a relay (b) associated with each finder for rendering its release circuit inoperative, a circuit for operating the relay (b) of the finder allotted to the calling line group closed upon the energization of line relay of a line in such group, a circuit closed by said relay and including the relays (b) of the finders through which the starter wire is extended, of a relay (180) for preventing the closure of said circuit, and a circuit for said relay including off-normal contacts of 50 all the finders in series.

In witness whereof, I hereunto subscribe my name this 18th day of November, A. D. 1916.

BERT G. DUNHAM.
